AIR CONDITIONING APPARATUS

William Marion Niehart, Los Angeles, Calif.

Application October 4, 1937, Serial No. 167,283

4 Claims. (Cl. 261—11)

This invention relates to apparatus for effecting a conditioning of air delivered to or circulated through an apartment.

One of the features of the present invention is the provision of a structure and method by which air is moved into or through an apartment, with a continuous withdrawal from the air current, before it enters the compartment, and the employment of the withdrawn air for effecting a cooling of the air current.

Another feature of the invention is the provision of a structure comprising essentially a self-contained unit including air-moving means, heat exchange surfaces, and spraying devices.

A further feature of the invention is the provision of a structure comprising substantially parallel and vertical heat exchange walls within a casing, together with means for establishing inlet and outlet headers at the top and bottom of the casing, these headers being individually connected with alternate passages between the heat exchange surfaces, together with means for effecting a conditioning and movement of the air in the structure.

With these and other features as objects in view, an illustrative manner of practicing the invention is set out below and in the accompanying drawing, in which:

Figure 1 is an upright sectional view through a preferred form of the apparatus.

Figure 2 is a horizontal sectional view substantially on line 2—2 of Fig. 1.

Figure 3 is a conventionalized perspective view of the upper ends of the air flow passages, with the casing walls broken away, to show the alternate closing of parts of these passages.

In the drawing, a casing C is formed, being comprised of the vertical walls 10, 11, 12, 13, the bottom wall 14, and the top wall 15. These walls define a structure which is closed save for the supply duct 16 by which air is moved to the apartment, a discharge duct 17 by which air is wasted to atmosphere—that is, discharged at a point outside of the apartment, and an inlet orifice 18 through which air is supplied to this vertical portion of the casing. It is preferred to combine this vertical casing with an associated housing for receiving auxiliary structures. For this purpose, the bottom wall 14 is extended and is sealed to side walls 19, a vertical end wall 20 and a top wall 21.

Within the vertical casing C are provided a plurality of substantially parallel and vertical partitions 25 which are of heat exchange nature; that is, they are preferably formed of metal and

adapted to establish a balance of temperature at their surfaces. These walls terminate short of the ends 14, 15 of the casing, and preferably have their upper and lower edges cut at an apex or angle.

At the upper end of the casing 15, the passages are each provided with a closing wall 26 which extends from a side wall 11, 13 to the apex of the shape of the parallel walls. The closing walls 26 are alternately disposed so that every other wall extends from the side wall 11, while the interposed walls 26 extend from the side wall 13. At the apex, a baffle 27 extends upwardly to a point near the top wall 15 and provides a proportioning flow-restricting member as will be set out hereinafter. This arrangement of the closing walls 26 divides the passages between the partitions 25 into two groups which are alternately arranged, the first one of these groups being in communication with the top header space 28 which is at the left of the baffle 27 in Fig. 1, and the second group being in communication with a top header space 29 which is at the right of the baffle 27 in this figure.

At the bottom of the casing, similar end closing walls 26a are provided, and are similarly disposed and arranged so that the first group of passages is in communication with a bottom header space 30, while the second group of passages is in communication with a bottom header space 31.

The inclined positioning of the edges of the individual heat exchange sheets 25 affords a larger inlet and outlet area for the respective passages.

The upper header space 28 is the outlet header for the first group of passages, and is in free communication with the duct 16 by which air is supplied to the apartment. The upper header space 29 is the inlet header for the second group of passages. The lower header space 30 is the inlet header for the first group of passages and is in communication by the orifice 18 with a fan, as will be described hereinafter. The lower header space 31 is the outlet header for the second group of passages and is in free communication with the discharge duct 17.

The bottom of the casing forms a sump 35 in which water collects by dripping from the walls of a second group of passages and from a moisture eliminator 36 which is positioned between the header space 31 and the discharge duct 17. Further, a constant water level is preferably maintained in the sump 35 from a water supply pipe 37 under control of a float-valve 38.

Within the auxiliary housing is provided a fan 55

40 which is driven by a belt 41 from a variable speed fan motor 42. This fan is connected to aspire air from the interior of the housing and deliver it by a short connection 43 to the orifice 5 18, and thus to the first inlet header 30.

Walls of the housing are apertured and provided with filters 45 through which air is drawn into the housing. This air may be taken wholly from the outside of the apartment, or in part 10 from the apartment and in part from a fresh air supply duct 46; suitable dampers (not shown) being employed for regulating the proportioning. In the event that all the air is being taken from the apartment, and a part is being discharged 15 through the discard duct 17, the pressure within the apartment is maintained by the normal leakages through crevices and other openings.

Within the auxiliary housing, further, is provided a pump 50 which is driven by a motor 51 20 and draws water from the sump through a pipe 52, and delivers the same by a conduit 53 and a swivel connection 53a to a spray pipe 54 which extends in the header 29 above the openings into the second group of passages. The pipe has a 25 plurality of orifices through which the water may be discharged under the pressure produced by the pump 50. This pipe is preferably mounted for rocking about its axis, and has an extension 55 projecting outside of the casing C and being provided with a lever 56 by which the pipe may be 30 rocked for determining the angular direction in which the water is being projected into the air. By changing the angularity, a portion of the water from the sprays can be thrown into the header 35 28 for humidifying the conditioned air stream moving into the apartment; and may thus be effective for further depressing the dry bulb temperature thereof, if desired. In Fig. 1, the cords 57 hang from the ends of the lever 56 and permit 40 easy adjustment of the angular positioning of the jets.

In installation, this unit may be located in the apartment or adjacent thereto, and provided with suitable connections from the apartment to the 45 filter openings 45 and to the air supply duct 16: a discharge duct extension is connected to the connection 17 if desired. The water pipe 37 is connected to a suitable supply of water.

In operation, the fan 40 is set in rotation by 50 energizing its motor 42, and the water pump 50 is similarly brought into operation. Air is drawn from the apartment and/or the duct 46, and delivered through the orifice 18 into the first inlet header 30, where it is divided and caused to flow 55 upwardly along the path of flow afforded by the first group of passages between alternate heat exchange walls, thus passing into the first outlet header 28 at the top of the casing. A major portion of the air then flows through the duct 60 16 to the apartment, while a minor proportion (depending upon the construction and adjustment of the proportioning member 27) passes over the top of this member and into the second inlet header 29 at the top of the casing, and 65 thence downwardly through the second group of passages which are separated from the first group by the heat exchange partition walls. Water is discharged into this portion of the air, and by adjustment of the direction of the jets, a slight 70 retardation may be imposed upon this portion of the air, or it may be accelerated; and therewith the rate of flow of the air as well as its effective water content may be modified. Part of the water is of course projected onto walls of the header 75 29, including the proportioning member 27 and

the closing walls 26, and part forms a film on the surfaces of the heat exchange members 25 themselves. The water not evaporated, however, trickles downward and collects in the sump. The air charged with particles of water passes to the 5 eliminator, and unevaporated water is separated back to the sump 35. Ultimately this air is discarded.

The action of the water upon the air, however, is to effect an evaporation into this air with a 10 simultaneous reduction of the temperature thereof. Hence, the air and water which is flowing downward in the second group of passages is at a lower temperature than the air which is flowing upwardly in the first set of passages, and a heat 15 exchange occurs so that the air in the first outlet header 28 is at a lower temperature than the air in the first inlet header 30.

The warm air in the first group of passages tends to warm the heat exchange walls and 20 thereby itself becomes cool.

Thus, it will be seen that the apparatus provides a means and operates by a method which comprises reducing the temperature of the incoming air toward its dewpoint by employing heat 25 transfer through a partition which is dry on one side and wet on the other. The total initial volume of the incoming air is first passed over the dry surface, and then is divided into a stream which flows to the apartment, and a second stream 30 which is then passed into contact with the wet side of the partition; so that the air contacting the wet side of the partition has already been reduced in temperature by its movement from the dry side. When the air first comes in contact with the wet surface, this surface is at or near the new wet bulb temperature, and by the action of heat transmitted through the partition from the dry side, and taken up by the water and air current, the wet bulb temperature of the air 35 flowing over the wet surface will increase until it has absorbed the heat being transmitted through the partition. In this way, the greater part of the heat taken from the air moving over the dry surface is absorbed through the process of increasing the wet bulb temperature of the air 40 on the wet side of the partition, and very little heat goes into the water to increase the sensible heat thereof; as it is preferred to provide only sufficient water for keeping the wet surfaces 45 properly moistened on the exhaust air side of the partition.

As an example of practice, if the dry bulb temperature of entering air is 80° and the corresponding wet bulb temperature is 67° , with a dew-point of 60.2° , the relative humidity of this entering air is 52%. In operating the structure, the air discharged by the duct 16 into the apartment had a dry bulb temperature of 66° , a wet bulb temperature of 62.5° , a dewpoint of 60.2° , and a 55 relative humidity of 81%. The discarded air had a dry bulb temperature of $74\frac{1}{2}^{\circ}$, a wet bulb temperature of 74° , a dewpoint of $73\frac{1}{2}^{\circ}$, and a relative humidity of 98%.

In another actual test outside air having a dry 65 bulb temperature of 92° , wet bulb temperature of 72° , dewpoint of 59° and a relative humidity of 33%, was reduced at constant dewpoint to a dry bulb temperature of 66° , wet bulb temperature of 61.5° , the dewpoint remaining at 59° and 70 the relative humidity changing to 78%. This air, raised 12° by the apartment had a dry bulb temperature of 78° , wet bulb temperature of 65.5° , the same dewpoint of 59° , and a relative humidity of 52%, an ideal condition for comfort.

As a further instance of practice, it may be pointed out that in certain western states, Arizona for example, it is not unusual to find temperatures even as high as 120°, with a humidity as low as 15%. Under such conditions, the unit 5 would deliver conditioned air at about 72°, and would maintain a room humidity of 45% and a temperature of 84°, or 55% humidity and 79° temperature.

10 It has been found that crimped aluminum sheets may be introduced between the partitions 25 to increase the contact between the air and the water in the second group of passages, which leads to a greater efficiency in the unit.

15 It is obvious that the invention is not limited to the manner of practice as shown and described, but that it may be varied in many ways within the scope of the appended claims.

I claim:

20 1. An air conditioning apparatus comprising means providing a casing, a plurality of substantially parallel heat-exchange partitions terminating short of the ends of the casing and providing separated passages in said casing, end closures 25 at each end of each passage for closing substantially half the area of each passage, said closures for alternate passages extending from opposite sides of the casing, a proportioning baffle at one end of the casing dividing the end space thereof 30 into a first outlet header space in communication with one group of the alternate passages and a second inlet header space in communication with the other group of alternate passages, a wall at the other end of the casing for dividing the end space thereof into a first inlet header space in communication with the said one group of passages and a second outlet header space in communication with the said other group of alternate 35 passages, means for supplying air to said first inlet header space and withdrawing it from the outlet header spaces, and means for spraying water into said second inlet header space, said water spraying means including spray devices opposite the openings of said other group of 40 passages, and means for shifting said spray devices for changing the angle at which the water is discharged therefrom to confine the water discharge to association with one group of passages only or for apportioning it between said passage groups.

50 2. An air conditioning apparatus comprising means providing a casing, a plurality of substantially parallel heat-exchange partitions terminating short of the ends of the casing and providing separated passages in said casing, end closures 55 at each end of each passage for closing substantially half the area of each passage, said closures for alternate passages extending from opposite sides of the casing, a proportioning baffle at one end of the casing dividing the end space thereof into a first outlet header space in communication with one group of the alternate passages and a second inlet header space in communication with the other group of alternate 60 passages, a wall at the other end of the casing for dividing the end space thereof into a first inlet header space in communication with the said one group of passages and a second outlet header space in communication with the said other group of alternate passages, means for supplying air to said first inlet header space and withdrawing it from the outlet header spaces and means for spraying water into said second inlet 65 header space.

sages and a second outlet header space in communication with the said other group of alternate passages, means for supplying air to said first inlet header space and withdrawing it from the outlet header spaces, and means for spraying 5 water into said second inlet header space, said water spraying means including spray devices and means for shifting said spray devices for changing the angle at which water is discharged therefrom and capable of effecting a projection 10 of water into the first outlet header space to cause a humidification of air moving therethrough.

3. An air conditioning apparatus comprising an elongated casing, a plurality of heat-exchange partitions providing separate passages extending 15 longitudinally in said casing, first and second air inlet connections at opposite ends of the casing, first and second air outlet connections at opposite ends of the casing and each disposed adjacent one inlet connection, said first inlet and outlet connections being adapted to take air from and deliver it to an apartment and being in communication with alternate ones of said passages to provide a first path of flow from the first inlet connection to the first outlet connection, means 20 for diverting a part of the air from said first path and delivering it directly to said second inlet connection, means for discharging air from said second outlet connection to a point outside of 25 said apartment, said second inlet and outlet connections being in communication with the other said passages to provide a second counter-current path of flow from said inlet connection to said second outlet connection, and means for contacting water with the air during its movement in 30 said second path of flow, the air diverting means including a proportioning member disposed between the first outlet connection and the second inlet connection for determining the quantity of air which moves from said first inlet connection 35 directly into said second inlet connection.

4. An air conditioning apparatus comprising a casing, a plurality of substantially parallel heat-exchange partitions terminating short of the ends of the casing and providing separated 45 passages in said casing, end closures at each end of said passages for closing substantially half the area of each passage, said closures for alternate passages extending from opposite sides of the casing, a proportioning baffle carried by the partitions at one end of the casing at adjacent ends of the open portions of the passages dividing the end space of the casing into a first outlet header space in communication with one group of the alternate passages and a second inlet header 50 space in communication with the other group of alternate passages, a wall at the other end of the casing for dividing the end space thereof into a first inlet header space in communication with the said one group of passages and a second outlet header space in communication with the said other group of alternate 55 passages, means for supplying air to said first inlet header space and withdrawing it from the outlet header spaces and means for spraying water into said second inlet 60 header space.

WILLIAM MARION NIEHART.
